UNITED STATES PATENT OFFICE

147,734

DESIGN FOR A TOASTER HOUSING

Charles W. Musser, Danville, Ill., assignor to Etc.,
Inc., Chicago, Ill., a corporation of Illinois

Application June 22, 1946, Serial No. 130,941

Term of patent 14 years

(Cl. D81—10)

To all whom it may concern:

Be it known that I, Charles W. Musser, a citizen of the United States, residing in Danville, in the county of Vermilion and State of Illinois, have invented a new, original, and ornamental Design for a Toaster Housing, of which the following is a specification, reference being had to the accompanying drawings, forming part thereof, in which:

Fig. 1 is a perspective view taken from a position in front and to one side of a toaster housing embodying my new design;

Fig. 2 is a front elevational view of the toaster housing shown in Fig. 1; and

Fig. 3 is a top plan view of the illustrated toaster housing.

I claim:

The ornamental design for a toaster housing, substantially as shown.

CHARLES W. MUSSER.
